UNITED STATES PATENT OFFICE.

EMMIT G. LATTA, OF FRIENDSHIP, NEW YORK, ASSIGNOR ONE-HALF TO
ADRIAN C. LATTA, OF SAME PLACE.

VELOCIPED.

SPECIFICATION forming part of Letters Patent No. 337,271, dated March 2, 1886.

Application filed November 23, 1885. Serial No. 183,639. (No model.)

To all whom it may concern:

Be it known that I, EMMIT G. LATTA, of Friendship, in the county of Allegany and State of New York, have invented new and 5 useful Improvements in Velocipedes, of which the following is a specification.

The object of this invention is to improve the construction of the steering-head and connecting parts, to render these parts more efficient, to reduce their weight, and to prevent the same from working loose when in use, while permitting them to be easily detached when required.

My invention consists, to these ends, of the 15 improvements which will be hereinafter fully set forth, and pointed out in the claims.

In the accompanying drawings, Figure 1 is a longitudinal sectional elevation of the steering-head and connecting parts. Fig. 2 is a 20 fragmentary sectional front elevation of the same. Fig. 3 is a detached elevation of the upper screw-center. Fig. 4 is a horizontal section in line x x , Fig. 1. Figs. 5, 6, and 7 are sections, on an enlarged scale, in lines x x , 25 y y , and z z , Fig. 2, respectively. Fig. 8 is a fragmentary top plan view, on an enlarged scale, of the brake-lever and the handle-bar to which it is pivoted. Fig. 9 is a horizontal section, on an enlarged scale, of the steering-head and handle-bar lug, showing the handle-bars secured therein. Fig. 10 is a plan view of the 30 inner ends of the handle-bars separated. Fig. 11 is an elevation of the key whereby the handle-bars are secured in the lug. Figs. 12 and 35 13 are cross-sections of the brake-lever in lines x' x' y' y' , Fig. 2.

Like letters of reference refer to like parts in the several figures.

A represents the steering-head, A' the handle-bar lug, B the spindle, B' the neck, and B² the backbone.

C represents the upper center screw, which is counterbored to permit the spindle to enter well into the upper part of the head.

In order to overcome the tendency of the 45 screw C to work loose, it is provided with a slow screw-thread, c , by which it is secured in the bore of the steering-head, and a quick thread, c' , to which is applied a check-nut, c^2 , which bears against the upper end of the steering-head. The two threads c c' are preferably

cut in opposite directions, one being a right-hand and the other a left-hand thread, so that if the thread c should tend to unscrew from the head before the check-nut is started the 55 quicker thread c' will cause the check-nut to crowd down upon the top of the steering-head and prevent the threaded part from further unscrewing. In this construction it is not necessary to tighten down the check-nut c^2 as hard 60 as is generally necessary in order to insure the locking of the threaded part c in the head. The threaded part c' may be made quicker than the part c , either by employing a coarser thread or by giving the thread a greater pitch; 65 but even when both threads are of the same pitch the center screw is more securely held in place by making the threads c and c' right and left hand. The neck B is made thin and flat, and works through a slot in the rear side 70 of the steering-head. The front portion of the backbone B² is curved upwardly, and the lug B³ at the rear end of the neck B' is curved downwardly to enter the curved portion of the backbone, whereby the backbone is brought 75 closer up to the head and the lug is prevented from turning in the backbone, while at the same time the weight of the parts is reduced.

D is the dust-guard, which is secured to the rear side of the neck, and which covers the 80 opening in the rear side of the steering-head.

d is an offset or shoulder formed on the upper side of the neck B' near its junction with the spindle B, and bearing against the dust-guard, which latter is secured to the offset d 85 by a screw, d'. This screw securely fastens the dust-guard to the neck, and is less expensive than a spring-fastening and permits the dust-guard to be easily removed when required.

E E represent the handle-bars, curved in any approved form and secured with their inner ends in the handle-bar lug A'. The handle-bars E are preferably made of tubing and strengthened at their inner ends by a short 95 piece of tubing, F, which is inserted into the handle-bars and projects slightly beyond the ends of the handle-bar lug, thereby strengthening the tubular bars at their joint and to a certain distance beyond the handle-bar lug. 100 The inner ends of the handle-bars are constructed with overlapping ends e e, which ter-

minate in hooks *f*, *f*. These hooks pass each other as the ends of the bars are inserted into the lug from opposite sides, and when the inner ends of the bars rest against each other 5 the hooks *f*, *f* leave an intermediate opening, in which a key, *g*, is inserted, whereby the handle-bars are secured to the lug. The key *g* wedges against the shoulders of the hooks and draws the overlapping ends of the handle-bars closely against each other, and prevents the handle-bars from turning in the lug. 10 The key also tends to spread the inner ends of the handle-bars and crowds the same against the sides of the lug, thereby causing the handle-bars to fit tightly in the lug. The key is made wedge-shaped only in the direction of its greatest width, and fits loosely in the lug *A* and the tubular stiffening-piece *F*. The key is preferably held in place by a nut, *h*. 15 By removing the key either one or both of the handle-bars can be quickly detached from the handle-bar lug. As the two ends of the handle-bars are exactly alike, the two bars can be interchanged, if desired. It is obvious 20 that solid handle-bars can be secured to the lug in the same manner, in which case the tubular stiffening-piece *F* is of course omitted, and that the stiffening-piece is not necessary when the tubular bars are made of heavy 25 tubing; but I prefer to construct the handle-bars of light tubing, and use this stiffening-piece in order to reduce the weight of the parts to a minimum, while maintaining the required strength. It is also obvious that 30 each handle-bar may be secured in place by a separate key, if desired.

H represents the brake-lever, preferably made of tubing and tapering each way from the point at which it is pivoted to one of the 40 handle-bars *E*. The inner end of the brake-lever rests against the brake *I*, and is secured thereto by a screw-bolt, *i*. As represented in Figs. 1 and 2, this bolt is constructed with wings, or otherwise prevented from turning 45 in the brake, and is screwed into the end of the brake-lever *H*.

In order to connect the brake-lever to the brake, the screw is inserted through the brake, in which it is held from turning, and the brake-lever is screwed upon the screw before these 50 parts are attached to the steering-head. When the parts are applied to the steering-head they are securely attached together and prevented from becoming disconnected. The outer end 55 of the brake-lever *H* is swaged into the form of a broad oval or spoon-shaped handle, *J*, as represented in Figs. 2, 12, and 13, whereby a large smooth handle is produced with the least weight.

K represents a bracket, which is secured to the front side of one of the handle-bars *E*, and to which the brake-lever *H* is pivoted by a vertical bolt, *k*, and a clip, *L*, which latter is brazed or otherwise secured to the brake-lever. 60 The clip *L* is provided on the rear side of the brake-lever with two jaws, which bear against the upper and lower sides of the bracket *K*,

and the pivot-bolt *k* passes through these jaws and the bracket, as clearly represented in Fig. 6. The bracket *K* is secured to the handle-bar *E* by two clamping strips, *M*, *N*, which embrace the handle-bar, and are secured to the bracket *K* at the front side of the handle-bar by screws *m* and *n*, respectively. 70

By using two narrow clamps instead of one wide clamp the necessary strength is obtained, while a better fit is secured to the curved handle-bar. 75

The clamp *M* is constructed of spring-steel, and its elastic front end, *m'*, bears against the rear side of the brake-lever and acts as a spring in operating the brake-lever, as represented in Figs. 5 and 8. The adjacent end of the bracket *K* is slotted, and the front portion of the spring-clamp *M* passes through the slot of 80 the bracket, as represented in Fig. 5. The screw *m* passes through this slotted portion of the bracket *K* and through the spring-clamp, so that the screw can be tightened without disturbing the elastic front end of the spring-clamp. This front end is preferably constructed with a reversed curve in order to render it sufficiently elastic, and this front part is also made somewhat wider than the part which embraces the handle-bar in order to give the 85 spring end the necessary strength. The clamp *N* passes around the rear and lower sides of the handle-bar and around the front side of the bracket *K*, as represented in Fig. 7. The fastening-screw *n* passes through the upper portion of the clamp *N*, and also through that 90 part of the lower portion of the clamp which rests upon the upper side of the bracket *K*, as represented in Fig. 7. When the clamp-screw *n* is nearly driven home, its point presses upon the lower part of the clamp on the under side of the bracket *K*, and thus tightens the clamp at both ends. By fastening the clamp in this manner greater strength and adjustability are 95 obtained than heretofore. 100

When a brake-spring of ordinary construction is employed, the bracket *K* may be secured to the handle-bar by two clamps, like the clamp *N*, or by a single wide clamp cut out in the middle to straddle the pivot and permit the clamp to closely fit the handle-bar. 105

I claim as my invention—

1. The combination, with the steering-head and spindle, of a center screw having right and left screw-threads, one engaging in the 110 steering-head and the other receiving a check-nut, substantially as set forth.

2. The combination, with the steering-head and spindle, of a center screw having a slow and a quick screw-thread, one engaging in the 115 steering-head and the other receiving a check-nut, substantially as set forth.

3. The combination, with the steering-head and spindle, of a center screw having right and left screw-threads of different pitch, the 120 slow thread engaging in the steering-head and the quick thread receiving a check-nut, substantially as set forth. 130

4. The combination, with the steering-head,

- of a spindle and neck provided with a lug, B³, curved downwardly from the neck, and a backbone, B², having its front portion curved upwardly to receive the curved lug B³, substantially as set forth. 5
5. The combination, with the steering-head and dust-guard, of a spindle and neck having an offset, d, forming a support for the dust-guard, and a screw, d', whereby the dust-guard is secured to the offset d, substantially as set forth. 10
6. The combination, with the handle-bar lug, of two handle-bars provided with overlapping inner ends, and an interposed key bearing against shoulders on said ends and drawing the ends toward each other, substantially as set forth. 15
7. The combination, with the handle-bar lug, of a handle-bar having its inner end constructed with a hook or shoulder, f, and a key, g, engaging against said hook or shoulder, and whereby the handle-bar is drawn inwardly, substantially as set forth. 20
8. The combination, with the handle-bar lug, of two handle-bars having overlapping inner ends, e, terminating in hooks or shoulders f, and a key, g, inserted between the shoulders of the handle-bars and tending to draw both bars inwardly, substantially as set 25 forth. 30
9. The combination, with the handle-bar lug, of the tubular handle-bars E and a tubular stiffening-piece, F, inserted into the inner portions of the handle-bars, substantially as set forth. 35
10. The combination, with the handle-bar lug, of the tubular handle-bars E, constructed with overlapping hooked ends, a tubular stiffening-piece, F, inserted into the inner portions of the handle-bars, and a key, g, passed 40 through the handle-bar lug, and the stiffening-piece F between the inner ends of the handle-bars, substantially as set forth. 45
11. A brake-lever for velocipedes, composed of a tube which is drawn down or tapered from its pivotal point toward its outer end, substantially as set forth. 50
12. A brake-lever for velocipedes, composed of a tube having its outer end flattened to form a handle, substantially as set forth. 55
13. A brake-lever for velocipedes, composed of a single length of tubing extending from the brake to the handle, substantially as set forth. 60
14. The combination, with the brake-lever and brake, of a connecting-screw held against turning in one of these parts and screwing into the other part, substantially as set forth. 55
15. The combination, with the brake-lever and brake, of the connecting-screw i, held against turning in the brake and screwing into the brake-lever, substantially as set forth. 60
16. The combination, with the handle-bar and the bracket K, secured thereto, of the brake-lever H and the clip L, secured to the brake-lever and pivoted to the bracket, substantially as set forth. 65
17. The combination, with the brake-lever and handle-bar, of the bracket K, secured to the handle-bar by a clamp of sheet metal embracing the handle-bar and secured to the bracket, substantially as set forth. 70
18. The combination, with the brake-lever provided with a clip, L, of a handle-bar, E, a bracket, K, secured to the handle-bar by clamps M N on opposite sides of the clip L, and a bolt whereby the clip is pivoted to the bracket, substantially as set forth. 75
19. The combination, with the brake-lever and handle-bar, of the bracket K, and the spring-clamp M, provided with an elastic front portion which bears against the brake-lever, substantially as set forth. 80
20. The combination, with the handle-bar and brake-lever, of the bracket K and the clamp N, embracing both the handle-bar and the bracket, and secured to the bracket by a screw, n, substantially as set forth. 85
21. The combination, with the handle-bar and brake-lever, of the slotted bracket K and the spring-clamp M, having its front portion passed through the slotted bracket and bearing against the brake-lever, substantially as set forth. 90
22. The combination, with the handle-bar and brake-lever, of the bracket K, the clamp N, embracing both the handle-bar and the bracket, and the screw n, passing through both ends of the clamp and the bracket, and bearing with its point against the lower portion of the clamp, substantially as set forth. 95 100

Witness my hand this 18th day of November, 1885.
